UNITED STATES PATENT OFFICE.

WILLIAM C. WATSON, OF PATERSON, NEW JERSEY, ASSIGNOR OF ONE-HALF
TO THEODORE Y. KINNE, OF SAME PLACE.

CAR-COUPING.

SPECIFICATION forming part of Letters Patent No. 411,176, dated September 17, 1889.

Application filed July 10, 1889. Serial No. 317,073. (No model.)

To all whom it may concern:

Be it known that I, WILLIAM C. WATSON, of Paterson, in the county of Passaic and State of New Jersey, have invented a certain new and useful Improvement in Car-Couplings, of which the following is a specification.

I will describe in detail a car-coupling embodying my improvement, and then point out the novel features in claims.

10 In the accompanying drawings, Figure 1 is a bottom plan view of a coupling embodying my improvement and portions of two cars. Fig. 2 is a similar view on an enlarged scale of a single car, certain parts being shown in section. Fig. 3 is an end view of one of the cars and the coupling arrangement thereon. Fig. 4 is a side view of the same. Fig. 5 is a detail, partly in section, showing the different positions into which the coupling-hooks may 20 be adjusted. Fig. 6 is a transverse vertical section taken on the line $x-x$, Fig. 4.

Similar letters of reference designate corresponding parts in all the figures.

25 A A' designate the bottom of cars, which may be of any suitable kind.

B designates draw-heads arranged upon the under sides of the cars and adapted to be moved lengthwise thereon. They are guided in their movements by means of guides a. (Shown as plates secured upon the under 30 sides of the cars.) Upon the edges of the guides a, adjacent to the draw-heads B, there are formed notches a', in which notches extend ribs or projections a², extending laterally 35 from the draw-heads. The projections prevent the movement of the draw-heads too far in one direction. The draw-heads are of frame-like construction and are hollow, their outer ends being of greater extent laterally 40 than their inner ends and being somewhat curved to admit of the various movements of the cars relatively to each other. At their rear ends the draw-heads are provided with shanks b, which shanks are also hollow and 45 are surrounded externally, as here shown, by coil-springs b', which coil-springs abut near one of their ends against the draw-heads and at the other against eyes b², formed upon plates b³, secured upon the under sides of the 50 cars. The shanks b extend loosely through said eyes, so that the draw-heads may move

freely to and fro. The springs b' tend to return the draw-heads to their normal positions after they have been pressed rearwardly out of such positions.

C designates coupling-hooks, which coupling-hooks are provided with hooking or engaging heads c and shank portions c'. The shank portions c' are of frame-like construction and extend rearwardly into the draw-heads B. Near their rear ends they are pivoted to shanks c², which shanks extend through the shanks b upon the draw-heads and to a considerable distance beyond the same. The shank portions c' are pivoted to 60 the shanks c² by means of pivots g, which extend outwardly to the exterior of the draw-heads and through longitudinally-extending slots g' formed therein. Near their outer ends the pivots g are shouldered, as at g², in 65 order to maintain said pivots in position within the draw-heads, and yet admit of the free longitudinal movement of the coupling-hooks. I extend the portions of the pivots beyond said shoulders through longitudinally- 70 formed slots in plates g³, arranged upon the exteriors of the draw-heads and secured near their other ends to the draw-heads by clamping-screws g⁵. The portions of the shanks c² beyond the eyes b² are screw-threaded and 75 engage nuts c³.

Surrounding the screw-threaded portions of the shanks c² are coil-springs c⁴, which coil-springs abut near one of their ends against the nuts c³ and at their other ends against washers c⁵, surrounding the shanks c² outside the eyes b². The outer extremities of the shanks b upon the draw-heads abut against the washers c⁵. It will therefore be seen that when the draw-heads are moved rearwardly they 85 are so moved not only against the resistance of the springs b', but also against the resistance of the springs c⁴. It will be further observed, however, that the coupling-hooks may have a longitudinal movement which is independent of the draw-heads when they are drawn outwardly, as they will be so drawn against the resistance of the springs c⁴ only. By this construction, should breakage occur 90 at the shanks of the draw-heads, there can 100 still be an independent movement of the coupling-hooks, and at the same time the

draw-heads will be maintained in position at their rearward ends by the shanks c^2 upon the coupling-hooks.

D designates springs (here shown as flat 5 springs) bent in such manner as to surround pins d , arranged in the interior of the frame-like shanks of the coupling-hooks. One of the arms of the springs D bears against the shanks of the coupling-hooks and the other 10 of said arms bears against the inner sides of the draw-heads. The tendency of these springs is always to force the coupling-hooks over toward one side of the draw-heads, and the springs are so arranged that upon adjacent 15 cars they will operate to force the coupling-hooks in opposite directions, or, in other words, so that the heads of the coupling-hooks will be firmly engaged. By these means, whatever the movements of the cars may be in turning curves, the coupling-hooks will always be maintained in firm engagement by the springs, as they may move for considerable 20 distances upon both sides of the center lines of the draw-heads. I have shown ranges 25 of movements which the coupling-hooks may have more clearly in Fig. 5.

E designates pull-rods arranged beneath the cars and adjacent to the ends thereof. Near their extremities these pull-rods pass 30 loosely through suitably-apertured guides e , secured upon the under sides of the cars. Extending from each of the pull-rods are projections e^2 , which projections extend through suitable apertures in the draw-heads B and 35 are of such extent that when the pull-rods are moved toward one side of the cars they will contact with the adjacent surfaces of the coupling-hooks and force the coupling-hooks over to one side of the draw-heads against the 40 resistance of the springs D and into a position where the hooks will be uncoupled, and also into such a position that should two cars come together while the coupling-hooks occupy such position they will not couple.

In Fig. 5 the position of the coupling-hooks shown in dotted lines at the lower side of the figure and numbered 1 is the position to which 45 reference has just been made. The coupling-hooks may also be moved into the position marked 2 in Fig. 5, in which position they will, when the cars are brought together, be coupled, as shown more clearly in Figs. 1 and 2, as the coupling-hooks are provided with reversely-extending beveled outer faces, 50 which, when the hooks are brought together, will slide past each other. After they have passed each other, the hooks will be sprung into engagement by the springs D. The coupling-hooks may also be moved into the position 55 marked 3 in Fig. 5 by the action of the springs D, in which position should two cars come together they would not couple. This position of the hooks will be attained when the cars are uncoupled and the projections e^2 on the pull-rods have been removed 60 from contact with the coupling-hooks. When occupying the second and third positions just

referred to the coupling-hooks are maintained therein by means of locks acting upon the pull-rods E. These locks comprise in this 7c instance notched plates f , secured upon the under side of the car. By reference more particularly to Figs. 1 and 2 it will be seen that the pull-rods E are provided upon their rear sides with projections f^4 . The projections f^4 extend into notches or slots f^3 , formed in the plates f.

Referring more particularly to Fig. 6, it will be seen that the notch f^3 consists of an upwardly-offset portion f^5 at the end of the 80 plate farther from the draw-head, an upwardly-offset portion f^6 at the end of the plate nearer the draw-head, and a downwardly-extending portion f^7 . The pull-rod E is also a rock-shaft and extends wholly across 85 the bottom of the car, it being provided about centrally with an offset portion f^8 , which extends downwardly and about the draw-head. Near the outer ends of the pull-rod and rock-shaft E the same is provided, as here shown, 90 with downwardly-extending arms or handles, which may be grasped to impart a longitudinal movement to said pull-rod and also to rock it when it operates as a rock-shaft. The rocking operation is for the purpose of causing 95 the engagement of the projection f^4 with one or the other of the offset portions f^5 f^6 f^7 of the notch f^3 , in order that the coupling-hook may occupy any one of the three positions specified, as desired. When the projection f^4 extends into the portion f^6 of the notch, 100 the coupling-hook will occupy the first position shown in Fig. 5. When the projection f^4 occupies the offset portion f^7 of the notch, the coupling-hook will be in its second position, 105 as shown in Fig. 5, and when the projection f^4 occupies the offset portion f^5 of the notch the coupling-hook will be in its third position. It will therefore be seen that by rocking the pull-rod and shaft E, as desired, and moving 110 it along not only will the coupling-hook be caused to occupy any desired position, but the pull-rod will be locked against longitudinal movement.

J designates a crank, the portion j of which 115 extends upwardly at the end of the car and above the roof. Said upwardly-extending portion extends through suitable bearings j' , secured to the end of the car. The lower portion of this crank extends through a suitable 120 aperture arranged in a projection j^2 , extending from the side of the pull-rod E, and in this instance about opposite the projection f^4 . The upper end of the portion j of the crank is provided with a handle j^3 , whereby the 125 crank may be rotated. When rotated it will cause longitudinal movement of the pull-rod, and by raising the crank up and down the pull-rod will act as a rock-shaft, which, when rocked, will cause the engagement of the projections j^4 with any of the desired offset portions of the notch f^3 . The upwardly-extending portion j of the crank extends loosely 130 through its bearings, so that it may move or

be moved freely up and down, and its weight is sufficient under certain circumstances to cause the rocking of the pull-rod and rock-shaft. This operation will occur when the 5 coupling-hook occupies its second coupling position. When in this position, and two cars are brought together, the coupling-hooks by their contact are forced laterally against the resistance of the springs D or toward their 10 third position. The strain upon the pull-rods is thereby at once relieved, because the coupling-hooks no longer contact with the projections e^2 upon the pull-rods. The weight of the cranks J will then operate to rock the 15 rock-shafts so that the projections f^4 will be raised against the portions of metal f^9 , which are between the offset portions f^5 f^6 of the notch f^3 . When the coupling-hooks have been locked together, the springs D will, when 20 motion of the car occurs, cause the coupling-hooks to swing from side to side, and thus move the projections f^4 beneath the offset f^6 of the notches. The weight of the crank will then further rock the rock-shaft, so as to force 25 the said projection up into the portion f^6 of the notch, thus locking the pull-rod against longitudinal movement. In this position the coupling-hooks may swing freely from side to side throughout the entire width of the mouth 30 in the draw-heads, and thus accommodate themselves to all the movements of the cars around curves and otherwise, the hooks being always maintained in engagement by the springs D. Instead of relying upon the weight 35 of the crank J, however, independent weights may be applied to the rock-shafts or a spring might be employed.

What I claim as my invention, and desire to secure by Letters Patent, is—

40 1. In a car-coupling, the combination, with a draw-head, of a coupling-hook pivoted within the same, a spring acting on said coupling-hook to force it in one direction, a pull-rod

extending upon both sides of said draw-head and adapted to contact with the coupling- 45 hook to move the latter in one direction, and a lock for securing said pull-rod in a position into which it may be adjusted, substantially as specified.

2. In a car-coupling, the combination, with a 50 draw-head, of a coupling-hook pivoted within the same, a spring for moving said coupling-hook in one direction, a pull-rod extending upon both sides of said draw-head and having a portion adapted to contact with the 55 coupling-hook to move it in one direction, said pull-rod also constituting a rock-shaft, an arm, and a notched piece with which said arm engages to lock said combined pull-rod and shaft against longitudinal movement, 60 substantially as specified.

3. In a car-coupling, the combination, with a 65 draw-head, of a coupling-hook pivoted within the same, a spring for moving said coupling-hook in one direction, a pull-rod extending to opposite sides of said draw-head and adapted to contact with the coupling-hook to move it in one direction, a lock for securing 70 said pull-rod in a position into which it may be adjusted, and a crank for causing the unlocking of said lock, substantially as specified.

4. In a car-coupling, the combination, with a 75 draw-head provided with a shank upon its rear end, of a spring surrounding said shank and operating to force the draw-head forward, a coupling-hook pivoted within said draw-head and provided with a shank extending through the shank of the draw-head, and a second spring surrounding said shank of the coupling-hook beyond the spring first 80 named and operating to draw said coupling-hook inwardly, substantially as specified.

WILLIAM C. WATSON.
